UNITED STATES PATENT OFFICE.

HUGO THUM, OF GRAND RAPIDS, MICHIGAN.

PRESS-COPYING DEVICE.

SPECIFICATION forming part of Letters Patent No. 398,758, dated February 26, 1889.

Application filed October 20, 1887. Serial No. 252,900. (No model.)

To all whom it may concern:

Be it known that I, HUGO THUM, of Grand Rapids, in the county of Kent and State of Michigan, have invented a new and useful

5 Improvement in Press-Copying Devices; and I do hereby declare that the following is a full, clear, and exact description of the same.

My invention is a portable copying device, designed to be used for taking copies of manuscript writing upon thin paper by both the 10 wet and dry processes now used.

The object of my invention is to provide a simple device which requires no press, and which may be used to copy letters without 15 leaving the desk.

A further object is to so construct it as to make it economical to manufacture and to adapt it for use as well with the dry process as with the wet process for taking copies of 20 manuscript writing, and, further, so that copies may be taken within a book or upon loose sheets.

My invention consists, primarily, of a base-plate provided with a flexible flap secured 25 thereto, the copying being done between the flap and the plate, as hereinafter described.

The invention also consists in the details, hereinafter fully set forth, for carrying the invention into effect.

30 Figure 1 represents a perspective view of my simple device. Fig. 2 is a section of the same, showing it in readiness for taking a copy by the dry process. Fig. 3 is a like section showing it arranged for taking a copy by the wet process. Fig. 4 represents the device in connection with a tray for holding moist sheets. Fig. 5 is a view of a modification for holding the moist sheets between the two parts 35 of the device.

40 In the drawings, A represents the base-plate of my press, which may be made of wood, metal, or glass, of a size and shape convenient for the purpose, and if made of wood it may be shod with metal, so as to prevent warping or twisting from the action of the moisture.

45 I prefer to have a flange extending downwardly at one end, which forms a shoulder for a bearing against the edge of a desk, which thus permits pressure to be applied, as will be 50 hereinafter described, away from the operator, the flange a holding the base-plate firm. At the same end that the flange is located, upon

the upper surface of the base-plate, I attach, in any suitable manner, a flexible sheet, B, which may be made of any material of a flexible 55 nature suitable for the purpose.

In the figures I have shown the base-plate as provided with a zinc cover upon its bottom and edges, and with a zinc strip forming the attachment of the flexible sheet to the upper 60 part of the plate by means of screws. This press is complete as thus constructed, and is capable of several distinct methods of taking copies from manuscript, which I will now describe: In the dry method of copying letters, 65 in which the ink used dries slowly, the letter to be copied is laid upon the base-plate with its written side up. Over this is laid a sheet of copying-paper, and over the two sheets is laid the flexible sheet B, and the copy is taken 70 by the operator rubbing his hands firmly over the flexible sheet; or, instead of his fingers he may use a smooth piece of wood or cork, to give a more even pressure. In Fig. 2 I have shown the sheets as arranged for taking the 75 copy by this method.

In the wet method of copying the letter is placed in a like manner upon the base-plate with its written side uppermost, the moistened sheet is placed upon the same, a sheet 80 adapted to absorb moisture is placed above the second sheet, and over the whole the flexible cover of the press is placed, and pressure applied thereto by the hands, or by a smooth piece of cork or wood, and the copy taken off 85 in this manner. The bibulous sheet interposed between the moistened sheet and the flexible cover is very desirable, as it prevents any spreading of the ink, and in absorbing the moisture from the wet sheet creates a current 90 from the manuscript page through the thin copying-paper which gives more perfect copying and aids the ink in penetrating the pores of the moistened sheets. It further aids in drying the sheet very quickly. 95

It will be understood that the operation is precisely the same whether copies are taken upon separate sheets or upon the pages of a book, as when applied to a book the base-plate is placed upon one side and the manuscript 100 page upon it, and the copy taken, whether by dry or wet process, by placing the sheet above the page and following out the method above described.

When the press is to be used with a wet process of copying, and it is desired to keep loose sheets damp within a tray, as that shown in Fig. 4, the press may serve as a cover to the tray. In this case I cover the bottom with zinc, as above described, which thus prevents the escape of the moisture, and also prevents the warping of the board, if wood be used for the base-plate. When it is not desired to use a tray such as that shown, a plate may be used either of metal or wood lined with metal, upon which the sheets may be placed and moistened, and after the surplus water has been drained off this plate, with the moistened paper upon its surface, may be placed upon the base-plate of the press and the paper covered by the flexible sheet, which will thus prevent the moisture in the paper from evaporating, and the moistened sheets will thus be in a position to be readily used. The moistened sheets of course may be wrapped up in a piece of oiled cloth or rubber, which will not only prevent evaporation, but will likewise keep the parts of the press from becoming damp.

I claim as my invention—

1. In combination, the base-plate and a covering-flap connected thereto, said flap being flexible and arranged to cover the plate, and by reason of said flexibility to lie directly upon all parts of the paper underneath, whereby pressure may be applied to all parts uniformly, substantially as described.

2. A device for copying letters, consisting of a base-plate and a flexible sheet, said sheet being movable in its relation to the base-plate and adapted to be used in connection therewith, substantially as described.

3. In the described device for copying letters, consisting of a base-plate and flexible sheet connected therewith and covering the upper surface, a flange extending downwardly from one end thereof, all substantially as described.

In testimony whereof I have signed my name to this specification in the presence of two subscribing witnesses.

HUGO THUM.
